Attorney

UNITED STATES PATENT OFFICE.

LIONEL M. WOOLSON, OF DETROIT, MICHIGAN, ASSIGNOR TO PACKARD MOTOR CAR COMPANY, OF DETROIT, MICHIGAN, A CORPORATION OF MICHIGAN.

INTERNAL-COMBUSTION ENGINE.

Application filed July 1, 1922. Serial No. 572,152.

This invention relates to internal combustion engines and particularly to the cooling means therefor.

One of the objects of the invention is to provide a method of cooling internal combustion engines in which steam is employed as the means for circulating the cooling liquid.

Another object of the invention is to provide means whereby the engine may operate at a rather high temperature so that it will be more efficient.

Another object of the invention is to provide steam means for delivering cooling water to the engine jacket and withdrawing it therefrom.

Another object of the invention is to eliminate mechanical means such as pumps for circulating the water through the cylinder jacket of an internal combustion engine.

Another object of the invention is to provide means for intermittently feeding water to the cylinder water jacket.

Another object of the invention is to provide means for forcing cooling water into the cylinder jacket and then withdrawing it therefrom and cooling it in a suitable radiator, the feeding and withdrawing being accomplished, in one form of the invention, through the same pipe.

Other objects of the invention will appear from the following description taken in connection with the drawings, which form a part of this specification, and in which:

Fig. 1 is an elevation and part sectional view of an internal combustion engine and cooling means made in accordance with this invention; and

Fig. 2 is a view similar to Fig. 1 showing another form of the invention.

Referring to the drawings 10 represents a cylinder block of an internal combustion engine having a water jacket 11 as shown in section in the upper left-hand corner. A radiator of usual type is illustrated at 12 and pipe connections 13 and 14 extend between the lower parts of the radiator and water jacket and the upper parts thereof respectively. It will be understood that the radiator 12 has a filling cap 15 by which water may be supplied to the system and this cap is adapted to be tightly closed so that pressure in the system may be maintained.

Connected to the upper part of the water jacket 11 or to the pipe 14 is a chamber 16 which may be termed a steam chamber, the connection to the pipe 14 being made through a smaller pipe 17. Surrounding the steam chamber 16 is a condensing jacket 18 which is vented to the atmosphere as at 19, this being the only vent in the system. The pipe 20 connects the lower part of the jacket 18 with the lower part of the radiator 12, or as particularly shown in Fig. 1 this pipe 20 connects with the pipe 13 adjacent the radiator. In the pipe 13 are one-way valves 21 and 22, the valve 21 being mounted between the radiator and the pipe connection 20 and the valve 22 being arranged between said pipe connection and the cylinder water jacket.

The operation of the system is as follows: With the system full of water, that is up to the top of the filler opening 15, and the engine started, the system will first operate as a simple thermosiphon system, the water after it is heated in the jacket 11 flowing through the pipe 14 into the radiator 12 and the cooler water from the radiator flowing past the valves 21 and 22 into the lower part of the water jacket 11. But as soon as the water in the jacket 11 is heated to the point where steam is formed the latter will enter the steam chamber 16 through the pipe 17 and will at the same time create a pressure in the system, which, by reason of the valves 21 and 22 will force the water in the radiator 12 upwardly through the pipe 20 into the condensing jacket 18, the air in the jacket 18 escaping through the vent 19. This cool water entering the jacket 18 will cause the steam in the chamber 16 to condense and this will, of course, create a partial vacuum in the chamber 16. This partial vacuum will, by reason of the valves 21 and 22, draw water upwardly through the water jacket 11 and pipe 13 thus withdrawing the water from the condensing jacket 18 through the pipe 20, the water in the radiator 12 remaining there because of the greater head of water in the pipe 20, the jacket 18 being higher than the top of the radiator 12. This cooler water entering the jacket 11 will, of course, cool the motor somewhat but as soon as it is again heated the steam will form and again enter the chamber 16 and the operation will be re-

peated. Thus there is an intermittent feeding of cool water to the jacket 11 and an intermittent withdrawal of water therefrom. There are no mechanical operating parts except the two valves 21 and 22 and these are operated merely by the flow of water past them.

Referring to the construction illustrated in Fig. 2, a somewhat similar cylinder block is illustrated at 10 but the main water jacket 30 thereof extends only around the sides of the cylinders. Over the tops of the cylinders is a jacket 31 which in effect constitutes a steam chamber somewhat similar to the chamber 16 of Fig. 1. Surrounding the steam chamber 31 is a condensing jacket 32 and this latter jacket is in communication through openings 33 with the upper part of the main jacket 30. A vent 34 to the atmosphere is provided in the upper part of the condensing jacket 32.

A radiator 12 is provided and is of the usual type except that its filling opening is so arranged that there is an overflow which prevents the radiator being filled more than slightly above the level of the tops of the cylinder heads. This filling openings is shown at 35 and is arranged to be tightly closed by a valve 36 which is screw threaded into the upper part of the radiator as at 37. An overflow pipe 38 is provided so that the radiator cannot be filled above the line 39 which indicates the water level.

The lower part of the radiator 12 is connected to the main water jacket of the engine by a pipe 40 and the upper part of the radiator is connected to the steam chamber 31 by a pipe 41. A very small port or opening 42 is provided between the lower part of the steam chamber 31 and the condensing jacket 32 and a plug 43 is shown as filling the opening made for the purpose of drilling the port 42.

The operation of the system illustrated in Fig. 2 is as follows: The system is filled with water to the level 39 thus providing a small amount of water over the cylinder heads in the steam chamber 31. With the valve 36 firmly seated the entire system is closed except for the vent 34 at the upper part of the condensing jacket 32. When the engine is started the heat in the cylinders quickly heats the small amount of water on the cylinder heads and steam is formed. The pressure of this steam communicated to the radiator through the pipe 41 forces the water from the radiator through the pipe 40 and upwardly through the main water jacket 30. The water in said jacket flows through the openings 33 into the condensing jacket 32, the air escaping through the vent 34. This cool water in the jacket 32 condenses the steam in the steam chamber 31 and a partial vacuum is formed therein. This partial vacuum is, of course, communicated to the

radiator 12 and water is withdrawn from the main jacket 30 through the pipe 40 into the radiator where it is cooled by the air passing therethrough. As the water recedes from the condensing jacket 32 steam is again formed in the steam chamber 31 and the operation is repeated.

It will be understood that various forms of the invention other than those described above may be used without departing from the spirit or scope of the invention.

Having thus described my invention, what I claim and desire to secure by Letters Patent is:

1. A method of cooling the cylinder of an internal combustion engine consisting in subjecting a small portion of the cooling water to a hot part of the cylinder thus causing expansion of said portion of cooling water, forcing, by this expansive action, some of the cooling water into condensing relation with the expanded portion thus condensing the latter, withdrawing, by the partial vacuum caused by this condensing action, the cooling water from its relation to the condensed portion, and subjecting the withdrawn water to a cooling medium.

2. A method of cooling the cylinder of an internal combustion engine consisting in subjecting a small portion of the cooling water to a hot part of the cylinder thus causing expansion thereof, forcing, by this expansive action, some of the cooling water into condensing relation with the expanded portion thus condensing the latter while at the same time causing some of the cooling water to flow in cooling relation to other parts of the engine cylinder, withdrawing, by the partial vacuum caused by this condensing action, the cooling water from its relation to the condensed portion, and subjecting the withdrawn water to a cooling medium.

3. In an internal combustion engine, the combination with the water jacket thereof, of a closed steam chamber, a condensing jacket surrounding the steam chamber, and means for causing steam to enter said chamber and condense therein.

4. In an internal combustion engine, the combination with the water jacket thereof, of a closed steam cylinder connected to the upper part of the water jacket only, a condensing jacket surrounding the steam cylinder, and means for intermittently forcing some of the cooling water into the condensing jacket.

5. In an internal combustion engine, the combination with the water jacket thereof, of a steam chamber, a condensing jacket surrounding the steam chamber, a radiator, and means for alternately forcing some of the cooling water from the radiator to the condensing jacket and from the condensing jacket to the cylinder water jacket.

6. In an internal combustion engine, the combination with the water jacket thereof, of a steam chamber, a condensing jacket surrounding the steam chamber, a radiator, and means actuated by the steam in said chamber for alternately forcing some of the cooling water from the radiator and from the condensing jacket to the cylinder water jacket.

10 7. In an internal combustion engine, the combination with the water jacket thereof, a radiator, and pipe connections from the lower part of the radiator to the water jacket and from the upper part of the water jacket to the radiator, of a steam chamber connected to the upper part of the water jacket, a condensing jacket surrounding the steam chamber, and a pipe connection extending from the lower part of the radiator 20 to the condensing jacket.

8. In an internal combustion engine, the combination with the water jacket thereof, a radiator, and pipe connections from the lower part of the radiator to the water jacket and from the upper part of the water jacket to the radiator, of a steam chamber connected to the upper part of the water jacket, a condensing jacket surrounding the steam chamber, and one-way valves between 25 the radiator and the pipe connection to the condensing jacket and between the said latter pipe connection and the cylinder jacket.

30 9. In an internal combustion engine, the combination with the water jacket thereof and a radiator, of a steam chamber connected to the upper part of the water jacket, a vented condensing jacket surrounding the steam chamber, and a pipe connection from 35

the lower part of the radiator to said condensing jacket.

40 10. In an internal combustion engine, the combination with the water jacket thereof and a radiator, of a steam chamber having an outlet to the radiator, and means actuated by the condensation of steam in said 45 steam chamber for forcing water from the radiator to the water jacket and then withdrawing the water from the water jacket into the radiator.

11. In an internal combustion engine, the 50 combination with the water jacket thereof, a radiator, and circulating pipe connections between the jacket and the radiator, of means to separate steam formed in said jackets, means operable by the pressure of 55 said steam to periodically condense said steam to form a vacuum, and means operable by said vacuum to circulate water through the jackets.

12. In an internal combustion engine, the 60 combination with the water jacket thereof, of means to condense steam formed in said jacket to create an intermittent partial vacuum, and means operable by the variation of pressure in the jackets to force water 65 into and out of said jacket.

13. In an internal combustion engine, the combination with the water jacket thereof of means to intermittently condense steam formed in the jacket to produce a periodic, 70 variation of pressure therein, and means operable by said variation of pressure to circulate water through said jacket.

In testimony whereof I affix my signature.

LIONEL M. WOOLSON.
